UNITED STATES PATENT OFFICE.

VAN RENSSLAER CHOATE KING, OF RADNOR, PENNSYLVANIA, ASSIGNOR TO KING'S CONCRETE CROSS TIE CORPORATION, OF NEW YORK, N. Y., A CORPORATION OF NEW YORK.

CONCRETE AND METAL CROSSTIE STRUCTURE.

Application filed June 21, 1924. Serial No. 721,397.

To all whom it may concern:

Be it known that I, VAN RENSSLAER CHOATE KING, a citizen of the United States, and resident of Radnor, in the county of 5 Montgomery and State of Pennsylvania, have invented certain new and useful Improvements in Concrete and Metal Crosstie Structures, of which the following is a specification.

- 10 This invention relates to concrete and metal cross tie structures. Its main objects are to produce such structures with a minimum of metal and a maximum of concrete at sufficiently low manufacturing cost to 15 permit the structures successfully to compete with wood ties and their fittings in point of expense; to make the structures in such form as to enable them to withstand in actual use the varying loads and complex 20 shocks, strains and stresses to which they are subjected; to produce the structures in such wise as to prevent endwise creeping of rails mounted on them, relatively to the rail clamping means comprised in the structures; 25 to reduce the number of such structures required for a given length of rail or track; to make the structures severally with aligned, adjustable heads each of which is of a dimension and weight readily handled; so to 30 construct each complete structure that its concrete-members will be insured against disintegration under load, shock and strain and that its mid-length portion will endure the vertical bending strains to which cross 35 ties are subjected, without impairment of the integrity of the concrete in the heads; and so to construct each complete structure that either or both of a pair of composite heads may have the outer end of its head 40 tilted upwardly and inwardly, its inward end tilted downwardly and the rail carried by it tilted laterally inwards. In some cases it will be desirable to have the outer ends of both heads in a structure tilted or slanted 45 in the upward and inward direction, while in other cases it will suffice to have the head on the outer side of a curve upwardly and inwardly tilted with its rail tilted laterally inwards and with the opposite head horizon- 50 tal and its rail vertical. In still other cases, especially on tangents, it will suffice to have both heads horizontal and both rails vertical. It is common practice to bank or elevate the ends of cross ties on the outward

side of curving tracks in order that by elevating the tie end and tipping the rail thereat laterally towards the inner side of the curve, centrifugal force exerted on locomotives and trains at the outer side of curves may be counteracted. By the present invention, in one of its forms, this desirable condition is readily effected, when and if desired. It is considered that even on straight or so-called tangent tracks, the inward tilting of both rails is frequently desirable and 60 in one of the forms of this invention, such tilting of both rails in a track is illustrated.

In the accompanying drawings forming a part hereof and illustrating the invention in its best now known forms,

Fig. 1 is a top plan view of the metal work, in one of two identical tie heads or ends and shows a connecting rod in threaded connection with the inner end, or connecting rod holder, plate of the metal work. The contour of the concrete portion of the head is indicated by dot and dash lines, the head being shown with its outer end tilted upwardly and its inner end tilted downwardly.

Fig. 2 is a side elevation of what is shown in Fig. 1, the contour of the concrete portion of the head being indicated by dot and dash lines.

Fig. 3 is a vertical, inner end elevation, partly in section at line 3—3 of Fig. 2, of what is shown in Figs. 1 and 2.

Fig. 4 is a vertical, outer end elevation of one of the tie heads.

Fig. 5 is a side elevation of one of the anti-creeping rail clamps.

Fig. 6 is an under plan view of what is shown in Fig. 5.

Fig. 7 is a top plan view of a pair of the ties in ballasted installation on a road bed and carrying parallel track rails severally clamped to tie heads by anti-creeping-rail clamps shown in Figs. 5 and 6, both heads being tilted with their outer ends higher than their inner ends and both rails being laterally canted inwardly one towards the other.

Fig. 8 is a side elevation of what is shown in Fig. 7, partly in section at line 8—8 of Fig. 7.

Fig. 9 is an enlarged sectional view at line 9—9 of Fig. 7 and shows a track rail having a flanged base located on a tie head with one anti-creeping-rail clamp in initial position

of assemblage and another in finally homed and locked position in which the clamp tongue is shown in its upwardly sprung and bodily deformed position.

- 5 Fig. 10 is a diagrammatic view of two laterally opposed, spaced apart tie heads with a rail clamped thereon, and, as indicated by a dotted line, showing that typical downward bowing of a rail, between two adjacent 10 ties, which occurs when a locomotive or train travels over track rails separated at intervals by cross ties.

Fig. 11 is a side view of the structure made with the heads horizontal.

- 15 Fig. 12 is a side view of the structure made with one tilted head, the other head being horizontal.

In Figs. 1, 2, 3, 7, 8 and 9, the concrete and metal heads are shown with opposed, 20 lengthwise extending rail and clamp bearing corner guard plates of metal.

Fig. 13 is a view in which both plates are made in one piece instead of in two pieces and covers the opposed, upper surface of 25 the head.

Fig. 14 is a view of an alternate arrangement of the rail and clamp bearing and corner guard plates in which the plates extend transversely across the upper surface 30 of the head.

Referring to the illustrated form of the invention, 1 illustrates the straight, mid-length, bottom portion of a metal reinforcing rod the ends 2 of which are turned severally upwardly and outwardly and terminate within but adjacent an end of the concrete block or member A of the head. The ends 2 are turned up in order to obviate shearing action thereof on the concrete during up or down vibrations of a head, such shearing action having been found to occur vertically at the end portions of straight reinforcing rods embedded in reinforced concrete ties and tie heads, in transverse relation to the rails. Said head comprises a pair of said reinforcing rods which are spaced laterally apart and extend lengthwise of the head, the middle straight portions 1 of the rods being adjacent but spaced above the under side of the head. The two heads in the cross tie structure are identical in construction. Description of one of them suffices for description of both. Each member of said pair of reinforcing rods is completely encased in the concrete, inwardly of a side wall thereof. They are thereby electrically insulated and protected from weather. Each pair of said reinforcing rods is designated as side reinforcing rods.

60 The straight portion 1 of each of these reinforcing rods is parallel with the bottom of the head, the concrete portion of which is a solid, cross-sectionally rectangular mass, preferably of a width greater than its height; and of a width greater than the

standard or usual width of ties, in order to reduce the number of the present structures required for a so-called panel or series of successive ties required for a given length of track rails, whereby the number of ties 70 per unit of length of track is substantially and materially reduced.

The mid-length, straight portions 1 of said reinforcing rods are in the corresponding mid-length portion of the head. The 75 upturned ends 2 extend nearly to the upper transverse corners of the heads and effect the necessary reinforcement of the outer end portions of the heads and at the same time by reason of their upturned form, obviate 80 the vertical shearing stresses above mentioned.

Each under, straight portion 1 of a side reinforcement rod has clampingly anchored to it, the under end of a pair of spaced 85 apart, upstanding metal anchor rods 3 the under ends 4 of which are bent upwardly and over the portion 1 of the associated rod in order to effect a fixed anchorage. The anchor rods 3 are completely embedded in 90 the concrete except at their upper ends which, above each side reinforcement rod, are severally fixed to a metal rail base clamp bearing and corner guard plate indicated by 6 applied in Fig. 3 to the opposed inner 95 edges.

In the preferred construction, two separated plates are mounted with their opposed inner edges 6 spaced apart and with their end edges alined, each on an upper, side corner portion of the concrete portions of the head. These plates 6 are preferably fixed to the upper ends 5 of the anchor rods by threads on the ends 5 and by threading such upper ends into threaded holes 7 in the 100 plates, the upper surfaces of which are flush with the upper surface of the concrete.

The upper, outer corner 6a of each plate 6 is sloped downwardly, forming a clearance 8 for the under side of a rail base. When 105 a locomotive or train is travelling over rails separated at intervals by cross ties, there is almost inevitably a downward bowing of the rail as at x (Fig. 10) under the travelling load which exerts an endwise 110 thrusting movement on bowed down rails in the direction of the travel of the load. Wood tie corners cushioningly endure the shock of these repeated end thrusts, but in concrete ties such repeated shocks effect disintegration 115 of the concrete, and it is a feature of this invention, by the clearances at 8, to protect the concrete opposed to the rail base from the disintegrating effect on the concrete of bowed down rails, by means of intervening metal corner guards formed with the downward curvature or sloping of the upper corner of each plate 6 whereby the clearances at 8 are effected.

Each rail base, clamp bearing and corner 130

guard plate 6 is preferably formed with a down-turned flange 9 of which the sloping corner 6^a forming the clearance at 8, is a part. The outer surface of the flange is flush with the outer surface of the concrete in the concrete, except at its inward end; an under and downwardly bowed, lengthwise reinforcing rod 13. These rods are midway between the sides of the head. 70

The plates 6 are immovably anchored to the mid-length portions 1 of the side reinforcing rods so that both upward and downward jolting movements of, and strains and stresses on, the plates are efficiently resisted not only by the reinforcing rods, but also by the intervening, hardened concrete between the rods and plates. This is important because in the present structure the rails are clamped to the plates 6, and the plates are an immovable part of the tie head. 75

When successive bowed down portions of the rails are successively freed from travelling, vertically downward bearing loads, the bowed down rail portions successively spring upwards and then exert upwardly pulling strains on the clamps, such strains being transmitted to the plates and from the plates 80

transmitted to the under portions 1 of the side tie rods accompanied by shock on the encasing concrete. The travelling loads, which bow down the rails between ties, also depress the tie heads in the ballast or ground 85

and the upward, return spring of the rails lifts the heads, so that the heads are vibrated vertically at frequently recurring intervals on passing of trains. It is therefore important firmly to anchor the under ends of the 90

anchor rods 3 on or in efficiently close relation to the side tie rods, near the bottom of the heads, in order to maintain the integrity of the concrete and prevent disintegration thereof by these recurrent vibrational shocks. 95

The plates 6 are severally formed with lengthwise alined, spaced apart, clamp bolt receiving, threaded sockets 10, one near each inward corner of a plate and spaced inwardly of the adjacent end edge of the plate. The intervening marginal portion 11 of the plate forms a bearing for the heel of a metal rail base clamp, outwardly of a socket 10. 100

The rail base seat is formed by the metal portions of the two plates, inwardly of the threaded sockets 10 which are transversely alined in two spaced apart rows, and by the exposed surface of the concrete between the plate edges. 105

Midway between its sides, each head A has embedded in its upper portion a lengthwise extending, upwardly bowed, reinforcing rod 12, the mid-length crown portion of which is approximately mid-way between the ends of the head, and adjacent, but spaced below, the upper surface of the head and completely embedded in the concrete, except at its inward, straight end. Directly under the reinforcing rod 12, there is completely encased 110

in the concrete, except at its inward end; an under and downwardly bowed, lengthwise reinforcing rod 13. These rods are midway between the sides of the head. 70

The crown of the under rod 13 is adjacent but spaced apart from the under side of the head and opposed to the crown of the upper rod 12. These rods 12 and 13 are called the intermediate reinforcing rods. Their outer ends are spaced apart adjacent, but inwardly of, the outer end of the head so that they are electrically insulated one from another and protected from weather. Their 75

inner, straight ends 14 are parallel, spaced apart one above the other and are severally threaded for reception each in a threaded metal plate which forms a connecting rod 80

work in each head. The outer surface of this connecting rod holder plate is flush with the inner end of the head and said holder plate is provided, between and in alinement 85

with the threaded holes 15, with a threaded connecting rod receiving socket 17. The threaded sockets 17 in the two opposed holder plates, one at the inner end of one head and the other at the inner end of the other head, are severally drilled and tapped with their axes outwardly and downwardly inclined relatively to the long axis of the head, when and if it is desired to connect each head tiltingly with the intervening 90

straight, connecting or coupling rod 18, the ends of which are reversely threaded at 19 in the corresponding, reversely threaded sockets 17. 95

By screwing each head on the end of the connecting rod, their upper rail bearing surfaces are brought into upwardly and inwardly inclined positions; and each head in a tie structure may be banked or given a support of earth or ballast in the road bed for maintaining the two heads with their connecting rod straight, in said inclined positions, whereby the inward sides of the rails carried by the heads will be inclined inwardly one towards the other. This construction is shown in Figs. 1 and 2, but if desired, as shown in Fig. 11, the connecting rod receiving sockets of said holders may be tapped and threaded horizontally so that both heads will be in alinement and with their axes coincident with the axis of the straight connecting rod. 110

If desired, as shown in Fig. 12, the connecting rod receiving socket of one of the holders may be inclined, as indicated, and the connecting rod receiving socket in the holder at the inner end of the opposite head may be horizontal whereby only one of the heads will be tilted, while the other will be horizontal, when installed in a road bed. 115

When the two heads are adjustably cou- 120

pled in any of the forms above referred to and the structure is installed in a road bed. on earth or ballast B, the connecting rod may be axially turned to adjust the two 5 heads relatively inwardly or outwardly, according to the rail gauge required. The holder plates when provided with the slanted, connecting rod threaded sockets 17 may have these sockets drilled and tapped with 10 their axes at various angles relatively to a side of a holder plate 16 in order to meet the varying requirements of banking or upward tipping of a head at the outward side of a curve, according to the degree of curvature. The general practice in connection 15 with wood ties and the like is to bank the tie ends at the outer sides of curves severally, from one inch to four inches above the position of the opposite tie end at the 20 inward side of the curve.

The holder plates 16 are shown rectangular and elongated in the direction of the height of the inner ends of the heads. The mid-length portion of every tie is subject 25 to vertical flexing movements from travelling loads, exerting recurrent strains on such mid-length portions. Consequently when the connecting rod, which is at the mid-length portion of the present structure, is 30 subjected to upward and downward strains, such strains are transmitted to the holder plates 16 which are solidly backed up by the concrete in the head, whereby the vertical strains are strongly resisted by the solid 35 concrete.

Each holder plate 16 in a head is solidly anchored in the concrete and made strongly 40 resistant to endwise displacement because of the reversely bowed, connecting rods 12 and 13 which are much more highly resistant to lengthwise strains, caused by spreading 45 of track rails, than would be the case if these reinforcing rods were straight with their crown portions severally adjacent, but spaced apart from the upper and under 50 surfaces of the head, they give to each concrete head, as a unit, a strikingly important element of strength in that on the passing 55 of a train, at which time the load on a head is vertically downwards, the upper rod 12 is in compression and the under rod 13 in tension; and on the return, upward spring 60 of the rails, after the loads have passed, the under rod 13 is in compression and the upper rod 12 is in tension. This structural condition is rendered very much more important in consequence of the vertical vibratory movements due to passing loads being increased by imperfect tamping or softening 65 of ground or ballast support of the heads.

The intermediate reinforcing rods 12 and 13 not only perform the functions of reinforcing rods, but also of anchorages for the 65 connecting rod holder plates and of alter-

nately operating compression and tension rods approximately in the axial planes of the heads and connecting rod.

The metal work in each head, as above described, is readily assembled up-side-down in a concrete form or mold and the concrete then solidly molded encasing of the metal work with the outer surfaces of the plates 6 and of the holder plates 16 exposed. If desired, the inner ends of the side walls may be oppositely tapered, the better to resist lateral track slippage under certain conditions.

The tie structures thus above described, each comprising a head coupled by a connecting rod, may be rock ballasted on a road bed in parallelism, as usual; and the heads, whether horizontal or tilted, may be adjusted endwise by turning their respective connecting rods to suit the rail gauge.

Considering a completed structure, it is noted that its metallic cross tying element comprises the two rods 12, the two rods 13, a pair of connecting rod holder plates 16 and a connecting rod 18 each end of which is fixed in a holder; that this assemblage is straight and that at each end of the connecting rod its therewith anchored, intermediate connecting rods 12 and 13 are located midway between the sides of the concrete portions of the heads. The metallic cross tying element forms as it were, the backbone of the unitary structure in which the holder plates extending vertically above and below the connecting rod ends resist vertical strains on the connecting rod and in which the upturned reinforcing rod ends 2 and the reversely curved ends of the intermediate reinforcing rods 12 and 13 are anti-shearing ends. When a structure containing 105 this assemblage is in use, said assemblage of rods 12 and 13, holder plates 16 and coupling rod 18 serves not only as an adjustably cross tying assemblage, but in association with the concrete member A 110

forms a solid, durable, convenient structure carrying in each head the side reinforcing rods with the thereto anchored rail bearing plates 6. On the passing of locomotives and trains, as above stated, the heads are given successive downward movements under the wheels and the immediately following up-spring of the rails, which have been bowed down between the heads, causes an upward movement of the heads. For this reason, the heads of a series of tie structures in use are successively vibrated in the vertical direction; and it is of the utmost importance that the tie heads be of a construction that renders the metallic elements therein immovable in the concrete for otherwise the bodily movements and the strains and tendencies to movement of the metal elements would disintegratingly affect the concrete.

As above stated, the track rails are heavily 130

and anti-creepingly clamped to the plates 6. Each clamp has a solid butt 20 which is cross-sectionally rectangular and the under surface of which is flat. The butt is formed 5 with a vertical clamp bolt receiving hole 21 the diameter of which is slightly greater than the shank of the associated clamp bolt. Inwardly of and spaced apart from the clamp bolt receiving hole, the clamp is provided 10 on its under side with an upwardly extending, vertical, rail base edge engaging shoulder 22, the height of which is slightly less than the thickness or height of the edge of the rail base flange R. Above the shoulder, the clamp is provided with an inwardly projecting, strong, upwardly springable and bodily deformable rail base flange engaging tongue 23. The under surface of this tongue is not machined but is more or less 15 rough, as indicated by y (Fig. 6). The clamp bolt receiving sockets 10 in the plates 6 are located and the clamps are so dimensioned that when a clamp is initially assembled with a seated rail base flange, the under, 20 outer corner or heel 24 of the clamp will rest on a clamp heel bearing 11 and the corner of the clamp shoulder will bear on the base flange near its upper corner, with the tongue in normal condition projecting over 25 the flange. The threaded end 25 of the clamp bolt is initially inserted in a clamp bolt receiving socket with the unthreaded shank 26 of the clamp bolt slightly loose in the hole through the clamp butt. In this 30 initial position of assemblage, a clamp bolt lock plate shown in the form of a thin metal plate 27, having between its ends a hole for passage of the clamp bolt, is interposed between the upper side of the butt and 35 the polygonal head 28 of the clamp bolt, the outer end of the lock plate being bent down at 29 across the end wall of the clamp and the other end of the lock plate being flat. In this initial assemblage, there is a triangular 40 space 30 between the under surface of the clamp butt, adjacent the corner of the shoulder and the plate 6. By screwing down the clamp bolt, the clamp body portion 45 31 between the shoulder and the clamp bolt is forced powerfully downwards, causing the shoulder to impinge against the base flange edge and the upwardly springable tongue to impinge with increasing downward force on the upper surface of the base 50 flange. As the clamp is finally homed, the triangular space is reduced and the upwardly springable clamp tongue is sprung upwardly and bodily deformed, causing a powerful, anti-rail-creeping pressure on the base 55 flange, with the portion of the clamp 31 between the shoulder and the inward wall of the hole through the butt, forced solidly between the flange edge and the opposed clamp bolt, the shank of which serves as an outward abutment at 32 for the clamp portion 60

31. The shoulders of the clamps at opposite sides of the rail base flange form the side walls of the rail seat in each head.

Among the practical advantages of the described structure in which the upwardly 70 springable and bodily deformed clamp tongues for prevention of rail creeping is an important feature, is the economic fact that the structures may be made mostly out of standardized metal stock commonly maintained by railroad companies in their own warehouses, that the parts may be assembled for concreting by the railroad workmen at regular established railroad shops and yards, or at intervals along roadbeds. 75

In laying and repairing tracks, the segmental tie structures effect a great economy of time and labor.

By rigidly clamping the rails to the plates, immovably mounting the plates on the heads, and anchoring the heads to the straight metal work referred to as the backbone of the structure, the supporting earth becomes an ultimate cushion in final effect for the ties, the structure of which has been found 90 in actual practice successively and practically to withstand heavy loads and the complex strains to which such structures are subjected.

In Fig. 13, the two corner plates of each of the above described forms are made in one piece with a continuous clearance forming slope of each outer opposed corner 6^a. The reference letter 6^b is applied to this one piece plate which fully covers the top 100 surface of a head. The only objection to this plate is that it weighs and costs more than the two separate plates shown in the preferred form.

In Fig. 14 the two rail bearings and corner guard plates 6 instead of extending, as above described, in the direction of the length of the head, extend transversely thereof being spaced apart by the upper concrete surface of the concrete member A. Each upper corner of each guard plate is formed with a clearance forming slope at 6^a, as above described.

The plates 6 whether in one piece or in a plurality of parts constitute rail base and clamp heel bearings; and their form and arrangement may be varied without departure from the invention.

The plate or plates 6 are conveniently made of sections of rolled, troughed angle 120 bars of any desired thickness, but it is desired to use as light weight metal as is consistent with strength and durability. Accordingly, for increasing the length of the threaded joint connections of the plates 6, 125 with the clamp bolts, a hexagonal nut 33 with its threaded bore registering with each threaded socket 10 is mounted in the assemblage of metal work by means of a temporary screw (not shown but readily under- 130

stood) and with its upper surface bearing against the under surface of a plate; and when the concrete is poured and solidified such nut becomes immovably anchored in the concrete with its upper surface forming a metal bearing for the under side of the plate 6. Similarly a polygonal nut 33 is screwed on the upper, threaded end 5 of each upstanding anchor rod 3 into a position to serve as a bearing for the under side of a plate 6 in the assemblage of metal work.

As there are two anchor rods 3 at each side of the metal work, the nuts may be adjusted into horizontal alignment and the plate or plates 6 leveled horizontally thereon, the under ends 4 of the anchor rods being bent upwardly after the anchor rods are screwed into the receiving holes 7. When the concrete is poured, these nuts become immovably anchored under bearings for the plates 6 opposed to them and each forms a prolongation of a threaded joint connection of each anchor rod 3 with the plate.

Similarly a nut 33 is located horizontally back of and in contact with each holder plate 16 by means of a temporary screw not shown, in the preliminary assemblage of metal work, the threaded bore of the nut registering with the adjacent threaded socket 17. When the concrete is poured, the nuts become immovably anchored in the concrete and severally increase the effective length of a threaded joint in which they are severally used. These nuts 33 are not clamp nuts but threaded sockets. Their polygonal form keeps them from rotational movements while the encasing concrete and the contacting plate serve to keep them from all endwise and lateral tipping movements.

When and if, as preferred, the plate or plates severally have a downwardly extending flange 9, the anchor rods 3 connected with each plate and being also clamped at their under ends 4 to a side reinforcing rod strongly hold the horizontal portion of a plate together with its flange on and over a corner portion of the head.

In the construction of Fig. 14, opposite corner portions of the concrete between the inward, transverse, opposed edges of the two plates shown are but negligibly exposed to the end thrust of bowed down rails, if at all. The adjacent rail bearing surfaces of the plates sustain the loads and thrusting shocks.

The opposed crowns of the reversely bowed reinforcing rods 12 and 13 are in the mid-length portion of a head and under the rail seat portion of the head, whereby the weight and shock of travelling loads are supported and sustained at the strongest portion of the head.

By making the clamp shoulders of slightly less height than the thickness of the edges of the rail base flanges, the whole power of each cooperating clamp bolt thread in its

receiving, threaded socket is effectively exerted for upwardly deforming the strong springable tongue on the homing of the clamp bolt, the tongue yielding upwardly from its root so that its upper surface becomes curved as shown at the right of Fig. 9. The described construction and its mode of operation have been found to result in holding rails against end creeping to a most important and novel degree.

To prevent travel of electric current from a rail and clamp heel bearing plate or plates on one head to the corresponding plate or plates on the other head, where, as is usually the case, the track is equipped with electric signalling or train control apparatus and in order that the apparatus may not be short circuited and the current confined to the intended rails at one side of the track, care should be taken to compact a sufficient thickness of concrete as an insulation between the upper rod 12 and the plates 6 or plate 6^b. As already stated, the side reinforcing rods are insulated one from another and from the outer metal work by the encasing concrete; and the outer ends of the intermediate reinforcing rods 12 and 13 are also electrically insulated one from another by the intervening concrete.

One of the advantages of the described structure lies in the fact that when a series of the ties are installed in a track and the rails are approximately anti-creepingly clamped to the heads, the highly objectionable, vertical wave motion of rails commonly occurring when rails are spiked to wood ties, on passage of trains, is approximately obviated because of the solidity of the tie heads and of the clamping of the rails thereto. In the case of rails held by spikes to wood ties, the spikes to a greater or less extent, become more or less loosened by the up and down vibration of the rails accompanied by their endwise moving tendencies in the direction of the train movement, and the wood ties are apt to rock on their lengthwise axes. The present structure approximately and in a most important way reduces such wave motion to a negligible degree and, at the same time, the tendency of the ties to rock on their endwise axes is greatly diminished by reason of the clearances at 8 at the upper corners of the ties when the clearances are opposed to the direction of the travel of the train.

The invention having been thus described in its best form now known, what I claim is:

1. In a railway cross tie comprising a pair of concrete and metal heads alinedly coupled by a rigid connecting rod, the combination of a pair of such heads severally comprising lengthwise extending, laterally spaced apart, side reinforcing rods severally having an anchor rod holding portion embedded in the

concrete below the upper surface of the head; at the upper portion of the head and spaced apart from each of said anchor rod holding portions by intervening concrete, a metal rail base and clamp bearing plate structure provided with a threaded clamp bolt receiving socket and a clamp heel bearing outwardly of said threaded socket; a plurality of spaced apart, upstanding anchor rods rigidly connected to each of said bearing plate structures and also in rigid anchored connection with the under side of each of the anchor rod holding portions of a side reinforcing rod; a connecting rod holder plate located at the inner end of each head and bearing against the concrete; lengthwise extending, embedded, intermediate, reinforcing rods in each head and having ends severally connected spacedly apart, to the holder, the holder between its connections with said rod ends being formed with a stiff connecting rod receiving socket; and a connecting rod connected with said sockets in the holders, one holder and the intermediate reinforcing rods connected with it, and the connecting rod all being in approximate alinement.

2. In the structure set forth in claim 1, a nut anchored in the concrete with its threaded bore registering with an alined threaded opening in a plate and with the plate adjacent the nut, whereby the effective length of a receiving thread in a constituent plate is increased by the juxtaposition of the threaded bore of the nut which also serves as a rigid support for the plate.

3. In the structure set forth in claim 1, the metal rail base and clamp bearing plate structure having transversely opposed portions severally forming a guard for an underlying, opposed, concrete corner portion of the associated head.

4. In the structure set forth in claim 1, the metal rail base and clamp bearing plate structure having transversely opposed portions severally forming a guard for the underlying, opposed, concrete corner portion of the associated head; and each upper corner of such guard sloping downwardly to form a clearance between the guard and the under side of a rail base, whereby disintegration of the concrete due to the end thrust of a bowed down rail is rendered negligible.

5. In the structure set forth in claim 1, the metal rail base and clamp bearing plate structure having transversely opposed portions severally forming a guard for the underlying, opposed, concrete corner portion of the associated head; said bearing plate structure having opposed, downwardly extending flanges bearing against the opposite sides of the concrete and together with the bearing plate structure being held immovably in position over upper corner por-

tions of the rail seat portion of the head by said anchor rods.

6. In the structure set forth in claim 1, the connecting rod receiving sockets in the holders being reversely threaded and the ends of the connecting rod being reversely threaded, whereby upon turning the connecting rod axially said holders with their respectively connected reinforcing rods may be drawn together or moved apart for drawing together or moving apart the connected heads.

7. In the structure set forth in claim 1, the connecting rod receiving sockets in the holders being reversely threaded, the connecting rod being straight and having reversely threaded ends and the axis of a threaded socket being inclined at an angle to and downwardly from the long axis of its associated head, whereby said head has its outward end tilted upwardly and inwardly for holding a rail carried thereby with its inward side canting downwardly and inwardly.

8. In the structure set forth in claim 1, the said intermediate reinforcing rods in each head being reversely bowed and located one above the other with their crowns opposed, the crown of one being adjacent the under side and the crown of the other adjacent the upper side of a head, and said opposed crowns being under the rail seat portion of a head.

9. In a concrete and metal railway cross tie structure, the combination with an embedded reinforcing rod and a downwardly flanged, rail, clamp bearing and corner guard plate having a threaded clamp bolt receiving socket of an upstanding anchor rod fixed to said plate and also to said reinforcing rod, the flanged plate bearing on the top margin and also on the upper side margin of the concrete and being spaced apart from the reinforcing rod by intervening concrete in which the anchor rod is encased.

10. A railway cross tie comprising a pair of concrete and metal tie heads and a rigid metallic coupling therefor; each tie head having a rail seat portion comprising therein anchored and spaced apart, metal, rail clamp holding members held against axial, endwise and tipping movements and severally formed with a threaded socket outwardly of and adjacent which the member has a clamp heel bearing and inwardly of and adjacent which the member has a rail base bearing; anchor rod holding members embedded in the concrete and upstanding anchor rods, said anchor rods being in anchored connection with the anchor rod holding members and with the rail clamp holding members; and, axially connecting the two heads, metal work comprising members embedded in each head and connected with a connecting rod

holder plate in each head; and a rigid connecting rod detachably connected at each end with one of said holder plates.

11. In a concrete and metal railway cross tie structure, the combination of a pair of spaced apart rail and clamp bearing plates; a plurality of reinforcing members having portions positioned below the level of said plates; and a plurality of upstanding anchor rods connecting each plate with one of said reinforcing members; the upper end portions of the anchor rods being screw threaded into threaded holes in the plates and severally provided with a nut inward of the free end of the threaded portion of an anchor rod and forming supports for the plates, and concrete encasing the reinforcing rods, the anchor rods and the nuts.

12. In a concrete and metal cross tie com-

prising a pair of concrete and metal heads 20 coupled by a rigid connecting rod; a connecting rod holder plate at the inner end of each head; in each head upper and under reinforcing rods having spaced apart ends anchored to a holder plate; in each plate 25 a threaded socket between said ends; back of and contacting with each plate an immovable member having a threaded bore registering with said threaded socket; concrete supporting each holder plate and enclosing in each head the reinforcing rods; and on each head rigidly anchored rail seat forming means; and rail holding devices.
